UNITED STATES PATENT OFFICE.

KLEMENS KOMACKI, OF CHICAGO, ILLINOIS.

FOOTPLATE LIGHT.

Application filed February 7, 1924. Serial No. 691,138.

To all whom it may concern:

Be it known that I, KLEMENS KOMACKI, a citizen of the United States, residing at Chicago, in the county of Cook and State of Illinois, have invented new and useful Improvements in Footplate Lights, of which the following is a specification.

This invention relates to a combined foot plate and illuminator especially adapted for use on the running boards of automobiles.

Briefly stated, an important object of this invention is to provide a combined toe plate and illuminator having a source of light which not only illuminates the toe plate to some extent but also directs a light laterally from the intermediate portion of the vehicle to which it is attached to serve as a signal to vehicles approaching from the side.

A further and equally important object of the invention is to provide a toe plate in which the front wall of the illuminator casing is arranged so that it inclines away from the surface of the toe plate whereby the accidental kicking of the front wall of the illuminator casing will merely result in the glancing of the blow from the plate and will not damage the same or the lens carried thereby.

Also, by inclining the front wall of the illuminator casing away from the toe plate dirt collecting pockets are avoided and the device is rendered more or less self-cleansing.

A further object of the invention is to provide an article of manufacture of the class described which is neat in appearance, durable in use, and cheap to manufacture.

Other objects and advantages will be apparent during the course of the following description.

In the accompanying drawing forming a part of this application and in which like numerals are employed to designate like parts throughout the same.

Figure 1 is a perspective view of the improved toe plate and illuminator applied;

Fig. 2 is a vertical transverse sectional view through the illuminator casing applied;

Fig. 3 is a group perspective illustrating the rear portion of the illuminator casing, and

Fig. 4 is a fragmentary perspective illustrating a modification of the invention.

In the drawing, wherein for the purpose of illustration is shown a preferred embodiment of the invention, the numeral 5 designates one of the running boards of the ve-

hicle and the numeral 6 designates a base or toe plate mounted upon the running board and secured thereto in any suitable manner. The forward end of the base plate 6 is provided with a downwardly projecting flange 7 which hangs over the edge of the running board and if desired suitable mud removing means may be mounted on the base plate or the flange of the same.

Fig. 3 clearly illustrates that an illuminator casing 8 is mounted on the rear portion of the base plate 6 and may be provided at its end walls 9 with inwardly projecting apertured ears 10 for the reception of fastening devices 11 by means of which the casing may be secured in position.

Fig. 3 clearly illustrates that the end walls 9 are of approximately triangular formation so that the front wall 12 will be disposed at an obtuse angle with relation to the plane of the base plate 6. Therefore, if the inclined front wall 12 is accidentally kicked the blow will not dent or damage the same, but will be glanced off. This is especially important because of the presence of the glass lens 14 extended over an opening 15 in the front wall. Of course, the lens 14 is strong enough to withstand any blows to which it might be subjected, but nevertheless the inclination of the front wall 12 and the lens 14 causes any blows striking the same to be glanced off without damage.

In carrying out the invention the fastening devices 16 extending through the ends of the lens holding frame 17 may be threaded into or through the front wall 12 to secure the lens 14 in place. The frame 17 and the lens 14 may be diamond or other shape without departing from the spirit of this invention.

Attention is directed to Figs. 2 and 3 which illustrate that the rear side of the wall 12 is provided with rearwardly projecting upper and lower segmental ribs 20, the ends of which are provided with apertured ears 21 for the reception of fastening devices extended through the ends of a cover plate 23. It will be seen that the cover plate 23 extends over and protects a bulb 24 mounted in a socket 25 carried by the lower rib 20. When the cover plate 23 is in place it will effectively protect the bulb and once the cover plate 23 is applied it is not necessary to remove the same to renew the bulb 24. The bulb may be renewed by detaching the lens 14 in the front wall 12.

Figs. 1, 2 and 3 illustrate the illuminator casing 8 as being constructed separably from and subsequently secured to the base plate 6, and if desired the casing 80 may be 5 formed integral with the base plate 81 as illustrated in Fig. 4. In this case, also, the front wall 83 of the illuminator is inclined at an obtuse angle with respect to the plane of the base plate 81 for causing blows striking 10 the same to be glanced off, the advantage of which has been fully pointed out.

The invention forming the subject matter of this application is especially designed to illuminate the base plate and to provide 15 a means to warn vehicles approaching from the side of the presence of the vehicle equipped with the light. Therefore, the illuminator serves a dual purpose.

It is to be understood that the several 20 forms of the invention herewith shown and described are to be taken merely as preferred examples of the same and that such minor changes in the arrangement and construction of parts may be made as will remain within the spirit of the invention and the scope of what is claimed.

Having thus described the invention, what is claimed is:

1. An article of the class described comprising a base plate adapted to be arranged upon the running board of a motor vehicle, an illuminator casing secured to the inner portion of the base plate and having triangular end walls and a front wall arranged 30 at an obtuse angle to the plane of the base plate whereby blows striking the front wall are glanced off, said front wall being provided with a lens, a pair of ribs carried by the front wall and arranged within the casing, a socket carried by one of the ribs, and a source of light connected to the socket.

2. An article of the class described comprising a base plate adapted to be arranged upon the running board of a motor vehicle, 45 an illuminator casing secured to the inner portion of the base plate and having triangular end walls and a front wall arranged at an obtuse angle to the plane of the base plate whereby blows striking the front wall are glanced off, said front wall being provided with a lens, a pair of ribs carried by the front wall and arranged within the casing, a socket carried by one of the ribs, a

source of light connected to the socket, and a cover plate extended over the rear edges 55 of said ribs for protecting said bulb.

3. An article of the character described comprising a foot plate adapted to be mounted upon the running board of a motor vehicle, a casing extended across one end portion of the foot plate and having a front wall arranged at an obtuse angle with respect to the plane of the foot plate whereby a blow accidentally striking the front wall will be glanced off, said front wall being provided with a detachable lens, and a source of light arranged within the casing and adapted to illuminate said foot plate and direct a beam of light longitudinally with respect to the foot plate.

4. An article of the character described comprising a foot plate adapted to be mounted upon the running board of a motor vehicle, a casing extended across one end portion of the foot plate and having a front 75 wall arranged at an obtuse angle with respect to the plane of the foot plate whereby a blow accidentally striking the front wall will be glanced off, said front wall being provided with a detachable lens, a source 80 of light arranged within the casing and adapted to illuminate said foot plate and direct a beam of light longitudinally with respect to the foot plate, and a cover plate 85 extending about and protecting the source of light within the casing.

5. A vehicle attachment comprising a foot plate adapted to be extended transversely of a motor vehicle, a casing formed separably from the foot plate and extended transversely of one end portion of the same and having triangular end walls, said triangular end walls being provided with inwardly projecting ears for the reception of fastening devices for securing the casing to the foot plate, said casing also being provided with a front wall inclined away from the foot plate and being connected to said triangular end walls, said front wall being provided with an opening, upper and lower ribs of 90 segmental formation secured to the front wall, a bulb having connection with one of said ribs, and a cover plate secured to the rear edges of said ribs.

In testimony whereof I affix my signature.
KLEMENS KOMACKI.
